UNITED STATES PATENT OFFICE.

WILLIAM E. BENDLER, OF SHEBOYGAN, WISCONSIN.

FIFTH-WHEEL.

SPECIFICATION forming part of Letters Patent No. 393,056, dated November 20, 1888.

Application filed March 1, 1888. Serial No. 265,845. (No model.)

To all whom it may concern:

Be it known that I, WILLIAM E. BENDLER, of Sheboygan, in the county of Sheboygan and State of Wisconsin, have invented new and useful Improvements in the Fifth-Wheels of Wagons; and I do hereby declare the following to be a full, clear, and exact description of said invention, reference being had to the accompanying drawings, and to the letters or figures 10 of reference marked thereon, which form a part of this specification.

My invention relates to improvements in the fifth-wheel or supporting bearing-plates and attachments by which the body of a wagon is secured to the front axle. It is a well-known fact that when one of the wheels of a wagon drops below or is elevated above the plane of the other wheels it has a tendency to twist the body of the wagon.

20 My invention consists in providing a slightly convex or angular supporting-bearing between the frontend of the body and the axle, which will permit of the slight inclination of the axle of the wagon when one of the wheels is raised or lowered, as mentioned, without inclining or twisting the body of the wagon.

My invention also relates to the construction and location of the head of the king-bolt or retaining-pivot by which the body and front 30 axle are secured together, whereby such parts are free to oscillate upon their supporting-bearings, as mentioned, without bearing against or clamping said retaining bolt or pivot.

The construction of my invention is explained by reference to the accompanying drawings, in which—

Figure 1 represents a front view, and Fig. 2 represents a longitudinal vertical section, of my device detached from the body and axle of a carriage. Fig. 3 represents a bottom view of the top plate, which is secured to the body of the carriage. Fig. 4 represents a top view of the bottom plate, which is secured to the axle and upon which the top plate shown in Fig. 3 rests. Fig. 5 represents an equivalent form of the device illustrated in Figs. 1 and 2, showing the convex bearing form on the lower surface of the upper plate. Fig. 6 is a cross-section of the contiguous bearing-plates of the axle 50 and body.

Like parts are represented by the same reference-letters throughout the several views.

A represents the upper plate or bearing, which is rigidly affixed to the center of the front end of the carriage-body in the ordinary 55 manner, and the same is provided with a downward-projecting annular flange, B, and central flange, C, which flanges B and C are nicely fitted to and adapted to operate within the upward-projecting annular flanges D and E, 60 formed upon the lower bearing-plate, F.

In the preferred form shown in Fig. 1 the upper edges of the annular flange are made slightly convex, terminating at obtuse angles α directly in front and rear of the axle, upon 65 which angles α the upper plate, A, rests, and is adapted to oscillate or be inclined, as mentioned.

As shown in Fig. 2, the upper surface of the upper plate, A, is provided with a recess, b, 70 for the head of the pivotal retaining-bolt G, so that the bearing-surface of the retaining-head is brought in line with the convex supporting-surfaces α , whereby it is obvious that with the rocking movement of the plate A upon its angular supporting-surface said movement will not be resisted by the retaining-pivot G, but instead, owing to the fact that the bearing-points of the retaining-pivot G are in line with the point of oscillation of the plate A, said 75 plate A is free to oscillate with but slight friction and without danger of cramping or bending the retaining-pivot.

The pivot G is preferably cast integral with one of the retaining-plates, and is provided 85 with an elongated head or lug, A', projecting from one side and at right angles to the pivot, and the thereon-secured plate is provided with a slot, C', upon one side of the pivot-receiving aperture for the reception of said lug A'. 90 When the pivot is inserted in the aperture, the plate thus secured is turned a partial revolution, so that the lug or head A' is brought out of line with the slot or aperture C', when the two plates are thereby locked together by 95 the lug A'. If desirous, the upper edge of the annular flange D may be made straight and a downward-projecting convex bearing-surface may be made on the upper plate, as shown in the equivalent form in Fig. 5.

H H are upward-projecting lugs formed integral with the plate A, which engage upon the respective sides of the cross-bar I, as indicated in Fig. 3, and thus serve to retain said cross-bar more firmly in place.

J J are downward-projecting lugs, which are formed integral with the lower plate, D, and are adapted to engage upon the respective sides of the front axle, K, as indicated in Fig. 4.

Having thus described my invention, what I claim as new, and desire to secure by Letters Patent, is—

1. The combination of the upper plate, A, provided with the annular downward-projecting flanges B and C, and lower plate, F, provided with upward-projecting annular flanges D and E, adapted to engage the annular flanges of said upper plate, said flange D being formed with a front and rear angular or convex bearing-surface for the thereon-supported plate A, substantially as and for the purpose specified.

2. The combination, with the contiguous bearing-plates of the front axle and body of the wagon having interlocking flanges, one of

which is provided with an angular or convex bearing-surface, of a retaining-pivot having its downward bearing-surface upon the upper plate in line with the convex bearing-surface of such plate, substantially as and for the purpose specified.

3. The combination, with the contiguous bearing-plates A and F, having interlocking flanges, one of which is provided with an angular convex bearing-surface, of the retaining-pivot G, cast integral with one of said plates, provided with a head or lug, A', projecting from one side of said pivot at right angles thereto, and the thereon-retained opposing plate, provided with a recess, C', for the reception of the head or retaining-lug A', by which said plates are locked together, substantially as and for the purpose specified.

In testimony whereof I affix my signature in presence of two witnesses.

WILLIAM E. BENDLER.
